CAPPING APPARATUS

Albert I. Shomperlen, Milwaukee, Wis., assignor
to Pittsburgh Plate Glass Company, Allegheny
County, Pa., a corporation of Pennsylvania

Application October 29, 1942, Serial No. 463,773

4 Claims. (Cl. 226—88)

This invention relates to container capping apparatus and it has for one of its objects the provision of an improved mechanism automatically operable periodically to grip and secure screw threaded caps upon containers.

Another object of the invention is to provide an improved capping head for securing caps upon containers.

Another object of the invention is to provide a capping apparatus which is adapted to be operated in conjunction with a container filling machine from which containers to be capped are supplied.

In the drawings:

Fig. 1 is a side elevation of a capping mechanism and supporting structure, parts of which are shown in cross section; Fig. 2 is a plan of essential parts of the structure shown in Fig. 1 with uprights shown in horizontal section; Fig. 3 is a plan of a container gripping device; Fig. 4 is a fragmentary vertical section, taken substantially along the line III—III of Fig. 3; Fig. 5 is a fragmentary vertical section of a capping head; Fig. 6 is a horizontal section taken substantially along the line VI—VI of Fig. 5; Fig. 7 is a fragmentary view, partially in section and partially in elevation, of shaft coupling elements; Fig. 8 is a horizontal section taken substantially along the line VIII—VIII of Fig. 5; Fig. 9 is a horizontal section taken substantially along the line IX—IX of Fig. 5; and Fig. 10 is a horizontal section taken substantially along the line X—X of Fig. 5.

In practicing the invention a capping apparatus 20 is employed in connection with a container filling machine which includes a conveyor 21 movable in a suitable manner past the capping apparatus. The type of container filling machine mentioned above is common in the art and is referred to merely to explain the manner in which the containers are prepared and moved to proper position for capping by the mechanism which is the subject of this specification. The capping apparatus includes a driven shaft 23 vertically rotatable in bearing supports 24 that are mounted upon a frame 26. Power for rotating the shaft is supplied from a suitable source (not shown) to a sprocket and chain gearing 28 connected to the shaft adjacent its lower end.

An intermediate portion of the shaft has rigidly secured thereon a cam structure 30 which includes an outer cylindrical wall 31 about which cam rail sections 34 and 35 are welded to provide a track on which a roller 36 travels in response to rotation of the shaft. A rocker arm or actuating lever 40 has a roller 36 rotatably supported

upon one end thereof and an intermediate portion of the lever has a boss 41 welded thereon through which a pivot bolt 42 is secured so as to extend horizontally therein. An upright post 5 43 rigidly secured upon the frame 26 supports clamping plates 45 upon one of which the bolt 42 is rigidly mounted. One of the plates is curved to fit snugly about the post. Suitable fasteners 46 clamp the plates 45 rigidly upon the post 43.

10 The end of the lever 40 opposite the roller 36 has a slot 47 formed therein through which an upright threaded pin 50 is loosely slidable. Washers 51 on the pin on opposite sides of the slotted lever end are engaged by compression springs 15 52 and 53 which surround the pin and are confined by means of washers and nuts 56 and 57, the latter of which are secured upon opposite end portions of the pin 50.

The upper end of the pin 50 is screwed rigidly 20 into a lug 58 that constitutes an intermediate part of a horizontal yoke 60 and extends laterally therefrom. This yoke can be composed of relatively thin bars 61 which are separated at their ends by means of the spacers 62 and which are 25 spaced in substantially parallel relation along their intermediate portions. The bars 61 are of such resiliency that they can be spread slightly. Bowed portions 63 are formed in opposite directions and centrally on the bars to form a bearing support for a vertical shaft sleeve section 65 which rotates therein. Interfitting thrust bearing parts 67 (Fig. 5) prevent the yoke 60 from moving axially of the shaft section 65, but permits free rotation of such section therein. Proper fitting of the bearing parts can be insured by 30 means of bolts 68 passing through the bars 61. Before the bolts are applied, these bars can be sprung sufficiently to receive the bearing portion of the sleeve 65.

35 40 A spline arrangement 69 slidably secures the shaft section 65 upon a vertical driven shaft 70 with respect to which it is vertically slidable, but non-rotatable. The sleeve section 65 is rigidly secured to a lower shaft section 71 in axial alignment therewith, and a clutch coupling 73 of 45 sleeve form is rigidly secured by means of a screw 74 to the shaft section 71. A keyway 76 formed in the inner wall of the sleeve coupling 73 cooperates with a keyway 78 in the upper end of 50 a clutch spindle 80 to receive a key 81 which prevents relative rotation between the sleeve and spindle. A set screw 83 threaded through the sleeve 73 against the key locks the sleeve and shaft rigidly together in proper axial alignment. 55 By manipulating one or both of the screws 74

and 83 the spindle 80 can be adjusted axially with reference to the shaft section 71.

The lower end of the spindle 80 is formed with an integral clutch disc or flange 84 frictionally confined between two clutch discs 86 and 87 which are mounted in a casing 89 forming a part of a capping head 90. These discs are keyed, as indicated at 91, in the inner wall of the casing and a third disc 92 is spaced upwardly from the disc 86. Coil springs 93 under compression have their ends fitted in sockets 94 in the opposing sides of the discs 86 and 92 to maintain frictional engagement of the discs 86 and 87 against opposite sides of the spindle disc 84. Set screws 96 threaded through a cover 97 of the casing contact the upper surface of the upper disc 92 for the purpose of compressing the springs 93 and thereby varying the frictional resistance offered by the discs 86 and 87 to the rotation of the spindle 80. This construction constitutes a slip clutch of variable resistance. The cover is bolted to the casing body by means of conventional fasteners 98.

A cup section 100 is keyed, as indicated at 101, to the bottom of the casing and is further secured thereto by means of screws 102. A pad 103 of yieldable or resilient material, such as rubber, resin, felt, or the like, is mounted in the cup section 100 and together with the casing is vertically movable toward a container 104 upon which a cap 105 is to be screwed.

Upright rods 110 extend slidably through openings 112 in opposite ends of the yoke 60 and are provided with stop nuts 113 screw threaded on the rods on the upper side of the yoke. A coil spring 114 surrounding each rod 110 is confined between the yoke and a pair of nuts 116 that are screwed upon the rod for adjustment of the spring with regard to its compression. Each rod 110 is connected at its lower end to the inner ends of oppositely extending toggle links 118 and 119 by means of a pivot pin 120. The outer end of the link 118 is pivotally supported, as indicated at 121, upon a bracket 123 that is rigidly mounted by means of bolts 124 upon a bed plate 126. The frame 26 rigidly supports the bed plate 126. The outer end of the link 119 is pivoted, as indicated at 128, upon a slidable jaw 130 which includes a plate 131 and a pair of rails 132 having a curved upright plate 134 welded to the forward ends thereof. Suitable padding 136, such as rubber, or other yieldable or resilient material, is secured to the curved plate for engagement with the container 104.

Bolts 138 extend through the plate 131 and through slots 139 formed in the rails 132. Thus the plates and rails are rigidly clamped together as a unit and they are relatively adjustable by manipulation of the bolts 138 in the slots 139. Each plate 131 extends laterally in opposite directions beyond the rails 132 and are slidably disposed in guides 140 (Fig. 4) formed by guide bars 141 secured longitudinally upon the inner sides of angle members 142 by means of bolts 143. In like manner bolts 145 secure the angle members 141 to the bed plate 126.

It will be apparent from this description that downward movement of the yoke 60 causes the rods to actuate the toggle links 118 and 119 and thereby move the clamping jaws 130 toward each other below the capping head 90. This downward movement of the yoke in response to the operation of the cam structure 30 is cushioned by the springs 53 and 114 and causes the clamping jaws first to grip the container and imme-

dately thereafter the pad 103 of the capping head, while rotating, will engage the cap to screw the latter upon the container. The degree of tightness of the cap upon the container is determined by resistance of the slip clutch members 84, 86 and 87. Continued rotation of the cam structure 30 simultaneously releases the pad 103 and jaws 136 from the container which is then carried away by the conveyor and another container with a cap placed thereon is moved into position to be similarly capped.

Although only one form of the invention has been shown and described in detail, it will be apparent to those skilled in the art that the invention is not so limited, but that various changes can be made therein without departing from the spirit of the invention or from the scope of the appended claims.

I claim:

20. 1. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke, simultaneously vertically to move the shaft and to reciprocate the jaws, said means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
25. 2. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
30. 3. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
35. 4. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
40. 5. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
45. 6. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
50. 7. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
55. 8. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
60. 9. In a capping apparatus, a rotatably driven axially slidable shaft, a thrust bearing rotatably mounted upon said shaft, said bearing carrying a yoke in axially fixed position with respect to the shaft, a head upon the lower extremity of the shaft, and being adapted to engage and spin a cap upon a screw-capped container, jaws below said head and being transversely reciprocable to engage and disengage a container to be capped, actuating devices for reciprocating the jaws, connecting means between the devices and the yoke and means to raise and lower the yoke comprising a shifter lever having a fixed pivot and further being pivoted at one end to the yoke and a driven cam having surface contours corresponding to the phases in the cycle of operation of both spindle and the jaws, operatively engaging a follower element upon the lever to operate the latter at predetermined intervals.
65. 10. A head for applying caps to screw cap containers comprising a housing, a cover upon the upper extremity thereof, an axially formed bearing in the cover, slidably receiving a spindle and normally rotating as a unit therewith a clutch disk fixed upon the spindle within the housing, a friction clutch disk keyed for axial movement within the housing and being adapted to engage the first-mentioned disk, a plurality of set screws threaded through the cover axially thereof and spring means interconnecting the friction disk and the set screws for exerting a yieldable pres-

sure actuating the friction disk into engagement with clutch disk, said set screws being adjustable to vary the pressure of the spring means upon the friction disk, and cap-engaging means fixed upon the lower extremity of the housing in non-rotatable relation thereto.

4. A head for applying caps to screw top containers, comprising a housing having a bearing within the upper extremity thereof, a spindle disposed for axial movement in the bearing and normally rotating as a unit therewith and being

provided with clutch plate within the housing, a friction disk non-rotatably secured in the housing but being movable longitudinally of the shaft to engage the upper surface of the plate, a spring engaging the upper surface of the friction disk, and a screw actuated pressure means in the upper portion of the housing and adjustably actuating the spring against the friction disk, and a cap engaging element rigidly fixed upon the lower extremity of the housing.

ALBERT I. SHOMPERLEN.
